CUE STICK

Julian A. Carreiro, Santa Susanna, Calif., assignor of a fractional part interest to Angelo N. Giordano, Canoga Park, Calif.

Filed June 23, 1971, Ser. No. 156,163

Term of patent 14 years

Int. Cl. D21—01

U.S. Cl. D34—5 BL

FIG. 1

FIG. 2

FIG. 3

FIG. 1 is a side elevational view of a cue stick showing my new design;

FIG. 2 is a top end view thereof; and,

FIG. 3 is a bottom end view thereof.

I claim:

The ornamental design for a cue stick, substantially as shown.
